UNITED STATES PATENT OFFICE

136,042

DESIGN FOR A TOOTHBRUSH

Charles Kenneth Veo, Newtonville, Mass.

Application February 11, 1943, Serial No. 109,530

Term of patent 14 years

To all whom it may concern:

Be it known that I, Charles Kenneth Veo, a citizen of the United States, residing at Newtonville, in the county of Middlesex, State of Massachusetts, have invented a new, original, and ornamental Design for a Toothbrush, of which the following is a specification, reference being had to the accompanying drawing, forming part thereof, in which,

Fig. 1 is a side elevation of the toothbrush showing my new design;

Fig. 2 is a plan view thereof.

Fig. 3 is a vertical sectional view on line 3—3

Fig. 1;

Fig. 4 is a sectional view on line 4—4 Fig. 1;

Fig. 5 is a sectional view on line 5—5 Fig. 1;

Fig. 6 is a sectional view on line 6—6 Fig. 1;

I claim:

The ornamental design for a toothbrush, as shown.

CHARLES KENNETH VEO.
